(57) **CLAIM**

The ornamental design for a threeway stopcock for medical synthesizer as shown and described.

DESCRIPTION

1. Three-way stopcock for medical synthesizer

1.1 : Front

1.2 : Back

1.3 : Top

1.4 : Bottom

1.5 : Right

1.6 : Left

1.7 : Perspective view 1

1.8 : Perspective view 2

1.9 : Perspective view 3

1.10 : Enlarged A-A sectional view

1.11 : Enlarged B-B sectional view

1.12 : Enlarged C-C sectional view

1.13 : D-D sectional view

1.14 : Enlarged view of E-e portion

This article is a three-way stopcock used mainly for a medical synthesizer that synthesizes, for example, radio-pharmaceutical used for positron emission tomography (PET). The long dash-short dash broken lines define the cut lines of the cross sectional views of the threeway stopcock for medical synthesizer and form no part thereof. The dash-dash broken lines depict portions of the threeway stopcock for medical synthesizer that form no part of the
